UNITED STATES PATENT OFFICE

RICHARD POPP, OF PARIS, FRANCE

DEVICE FOR SETTING TO ZERO FOR TAXIMETERS

Application filed June 25, 1924, Serial No. 722,295, and in France June 25, 1923.

The present invention concerns taximeters, and consists in a device, whose characteristics 5 parts are intended to ensure the return of all the organs to their original position, when the flag is set to zero, before the flag can again be lowered for another journey.

Existing taximeters are set to zero by a complete revolution in a counterclockwise direction, that is to say that the flag shaft does 10 not come back to its point of departure to return to zero.

It can move between the various tariffs, but when it has passed tariff 1 for example, it cannot reverse its motion, and in the same way, 15 when it has passed tariff "payment," it cannot reverse its motion.

Between tariff 1 and tariff "payment," it can move backwards or forwards as required.

This being admitted, in taximeters working 20 in this way, it frequently happens that the springs or organs for setting to zero, have not had the time to act completely on the indicating drum if it is changed brutally from the position "payment" to the position "tariff 1;" instead of registering the minimum charge, it happens that certain figures of the previous journey remain visible and this can be the source of errors or fraud.

The annexed diagrams, Figures 1, 2 and 30 3, clearly show the improvements which are the objects of this invention.

Referring to Figures 1 and 2, the defect noted above is avoided by fixing a ratchet 2, cut in the direction of the arrow, to the flag 35 shaft 1. When the flag is lowered, it is obliged to remain in the acquired position, because it is held there by the retaining pawl 3.

This ratchet has no teeth between the position "tariff 1" and "payment," but it is again toothed between the position "payment" and "free;" apart from this there is nothing particular about this retaining device.

On the same flag shaft a pinion 4 is fixed, which engages with a toothed sector 5, and the latter after turning through an angle of 45° for example, will butt up against pinion 4, which as Figures 1 and 2 show, has only 50 the same number of teeth as sector 5. Pinion

4 is fitted with a pin 6, and sector 5 is fitted with a pin 7.

Sector 5 is brought back to its starting point by a spiral spring 8, Figure 1, the return movement of the sector 5 being limited 55 by a projection 22 thereon engaging a stationary stop lug 23. Finally an arm 9 oscillating about the point 10, is raised or lowered as required by the pin 7 fixed on sector 5. This lever 9 is pulled downwards by the 60 helical spring 11 until it rests on the pin 12.

The action is the following: The flag is at the zero position, that is to say vertical. In this position, the sector 5 can move backwards, due to the notch 13, which is cut in the 65 toothed pinion 4.

In this position, the pin 7 has raised the lever 9, Figure 1. It will be observed that when the flag is lowered the toothed portion of pinion 4 will engage with sector 5 up to the moment when there are no more teeth on pinion 4. As will be understood, the portion of the pinion 4 lying intermediate the notch 13 and the toothed portion opposite said notch is of such radius as to prevent the sector 5 from returning to initial position under the influence of the spring 8 when the wheel 4 has advanced to the position shown in Fig. 2.

Lever 9 is lowered and rests on pin 12, Figure 2. The position "payment" is thus 70 reached. At this moment, if by a violent movement, the flag is passed from "payment" to "tariff," pin 6 will butt up against lever 9. Pinion 4 will only be freed when sector 5 due to notch 13, is allowed to come back and raise 75 lever 9, which then frees pin 6.

The time that the sector takes to reverse its motion and free pin 6 is longer than that necessary for the drums and other organs to return to zero (the movement of return 80 the zero position begins at about 23° from the vertical). The result is that the appliance will always be at the zero point before the flag is again lowered, whatever may be the speed or violence of rotation of the latter.

Referring to Figure 3, the diagram has reference to a variation of the stopping time required for the flag at each return to zero, based on the same principle, and which is obtained by using a washer 14, simply fixed on 100

the flag and provided with a notch 15, on which is fixed a finger 16.

This washer 14, by means of the finger 16, actuates a pin 17 which is fixed on a sector 18, 5 which is held onto a fixed pin 20 by the spring 19.

It is evident that, by turning the washer 14 in the direction of the arrow, the finger 16 as soon as it meets the pin 17, will bring with 10 it the sector 18, up to the moment when the finger 16 is freed from the pin 17. At this moment, thanks to the notch 15, sector 18 can return to its original position. This stopping time of the washer is necessary to enable the sector 18 to reverse its motion and is 15 sufficient for the taximeter to be set to zero.

On the other hand, if the movement of the flag is violent, the extremity 21 of the washer 14 will butt up against sector 18, the notch 20 15 not allowing sector 18 to continue its stroke once finger 16 is free.

Claims:

1. In a taximeter, a flag shaft therefor, a spring returned rotatable member, means for 25 transmitting movement of the flag shaft to said rotatable member throughout a portion of revolution of said flag shaft, a cutaway portion in said means cooperating with said rotatable member, and means for locking the 30 flag shaft against rotation under certain conditions which is controlled by said rotatable member and released when said rotatable member is returned by its spring through said cut away portion.

2. A taximeter as claimed in claim 1, characterized by the provision of means acting during a portion of revolution of the flag shaft for preventing reverse rotation thereof except between "payment" and "tariff" 40 positions.

3. A taximeter as claimed in claim 1, characterized in that the means for locking the flag shaft against rotation includes a pivoted lever, means on the rotatable member for displacing the lever to inoperative position, and 45 an abutment carried by the flag shaft.

In testimony whereof I have signed my name to this specification.

RICHARD POPP.
